W. H. W. HAMILTON

VACUUM REFRIGERATOR

Filed April 12, 1924

FIG. 1.

FIG. 3.

FIG. 2.

INVENTOR
W.H. W. HAMILTON
BY *George Griffith*,
ATTORNEY.

UNITED STATES PATENT OFFICE.

WILLIAM H. W. HAMILTON, OF ROCHESTER, NEW YORK, ASSIGNOR OF ONE-HALF TO
JOSEPH H. HUNTSMAN, OF SAN FRANCISCO, CALIFORNIA.

VACUUM REFRIGERATOR.

Application filed April 12, 1924. Serial No. 706,028.

To all whom it may concern:

Be it known that I, WILLIAM H. W. HAMILTON, a citizen of the United States, and a resident of the city of Rochester, in the county of Monroe and State of New York, have invented certain new and useful Improvements in Vacuum Refrigerators, of which the following is a specification.

The present invention relates to refrigerators provided with means of insulation of a character insuring the least possible radiation, and has for a principal object the employment of principles of construction that will reduce to a minimum the outflow and inflow of heat from the storage compartments of refrigerators, through the enclosure of such compartments within double walls enclosing a "vacuum" and this "vacuum", in turn, enclosed within a third spaced wall; thus affording an air-space as between atmosphere and "vacuum". To further reduce radiation across both air-space and vacuum-space, insulation substances are provided for the exterior surface of the outer wall of the double walls enclosing the "vacuum" and the interior surface of the third wall, as well as reflective surfaces for the interiors of the walls of the vacuum-space.

In the accompanying drawings, forming a part of this specification and in which similar characters of reference refer to like parts, throughout,

Figure 1 is a view, in perspective, with walls broken away to disclose their arrangement, the relative positions of ice and storage compartments, air-pump connection with "vacuum", and gauge for indicating degree of "vacuum";

Figure 2 is a broken-into side elevation, showing air-space, vacuum-space, air-pump, gauge, ice-compartment and storage-compartment.

Figure 3 is a mid-section of a modification, or simplified form of construction, in which the air-space has been dispensed with, the vacuum-space remaining as the only means of retardation to radiation; and

Figure 4 is a detail of an air-pump valve. Referring more particularly to the draw-

ings, 1 indicates a refrigerator, 2 the ice-compartment, 3 the storage compartment, 4 the vacuum-space, 5 and 6 the walls thereof, 7 the air-space, 8 and 9 the walls thereof, 10 and 11 doors opening respectively to ice and storage compartments, 12 an air-pump having a ball-check plunger for lowering the pressure within the vacuum-space in the event of the intrusion of air through leakage, 13 a pressure gauge, connecting with the vacuum-space, for determining whatever degree of pressure there may be within this space, and 13, 14 reflective surfaces of the vacuum-space walls, affording, as constructional features, additional bad radiation elements. In the modification, as presented in Figure 3, no factor other than that of the vacuum-space is employed as a means for the prevention of radiation, providing a less expensive refrigerator, though at the cost of a slightly increased radiation. As is to be observed, the more perfect the means for the prevention of radiation, the more highly efficient the device becomes as a refrigerant, a small amount of ice under conditions thus provided proving sufficient for ample refrigeration over an extended period.

Having thus described my invention, I claim as new, and desire to secure by Letters Patent:

1. A refrigerator having a chamber surrounded by double walls enclosing a "vacuum", said chamber being divided into an ice-compartment and a storage-compartment, openings leading respectively into said compartments, closures for said openings comprised respectively of double walls also enclosing vacuum-spaces a third wall spaced from and enclosing said double walls and providing an air-space therebetween, an air-pump mounted within said vacuum-space for securing and maintaining "vacuum" within said vacuum-space, and a gauge for indicating the degree of "vacuum" within said space.

2. A refrigerator having a chamber surrounded by double walls enclosing a "vacuum", the said walls being provided with reflective surfaces and the said chamber being divided into an ice-compartment and a

storage compartment, doors, as closures for said openings, comprised respectively of double walls enclosing "vacuums", a third wall spaced from and enclosing said double walls and providing an air-space therebetween, an air-pump mounted within said vacuum-space for securing and maintaining "vacuum" within said vacuum-space, said pump having a ball-check plunger adapted to hold the vacuum and a gauge for indicating the degree of "vacuum" within said space. 16

WILLIAM H. W. HAMILTON.
